LUBRICATING DEVICE

Otto B. Clark, Chicago, Ill., assignor to The Lubrication Corporation, Chicago, Ill., a corporation of Delaware

Application March 22, 1935, Serial No. 12,401

6 Claims. (Cl. 221—47.1)

This invention relates to pumps and more particularly to lubricant dispensing pumps and to novel operating mechanism therefor.

One object of the invention is to provide a pump including novel operating mechanism which is simple and reliable and which can be operated from any desired point.

According to one desirable arrangement, the invention is embodied in a portable lubricant pump constituted by a vertical reservoir having a cylinder and piston at its lower end and an annular support rigidly secured to the cylinder. An operating member is provided constituted by a hub portion resting on the support and an annular ring encircling the lower part of the reservoir and connected to the hub portion. The hub portion is grooved to receive the support and engages the piston at its center so that depression of any part of the ring causes the hub to pivot about the support and move the piston in the cylinder. A spring is preferably provided to urge the piston out of the cylinder into engagement with the hub; thus holding the hub against the support.

Other objects, advantages and novel features will appear from the following detailed description when read in connection with the accompanying drawing showing one embodiment of the invention. It will be understood, however, that the drawing is for the purpose of illustration only and is not to be taken as a definition of the scope of the invention, reference being had for this purpose to the appended claims.

In the drawing wherein like reference numerals indicate like parts throughout the several views:

Fig. 1 is a side view of a portable lubricant pump embodying the invention;

Figure 2 is a partial section taken substantially at the center of Fig. 1; and

Figure 3 is a partial section on line III—III of Fig. 2.

Referring more particularly to the drawing, there is shown a portable lubricant pump embodying the invention constituted by a vertical cylindrical reservoir 10 supported on legs 12 which have suitable wheels 14 and/or casters 16. The reservoir has a lid 18 secured in place by any suitable means such as wing nuts 20 and may, if desired, be provided with an inlet 22 for air under pressure and a pressure gauge 24.

The reservoir may be filled with lubricant directly but is preferably intended to receive a cartridge 26 having an outlet in one end for sealing engagement with an outlet nipple 28. The opposite end of the cartridge (not shown) has a

slidable fit therein and is adapted to be forced down by air pressure, either atmospheric or super-atmospheric, to force lubricant out of the outlet. With this arrangement, when a cartridge is empty it is removed and replaced by a full one. 5

The legs are formed integral with or secured to a suitable block 30 to which the reservoir is also secured as clearly shown in Fig. 2. This block is drilled to provide a cylinder 32 which is connected to the inlet nipple 28 and an outlet passage 10 34 also communicating with the cylinder. An outlet pipe 36 is screwed into the outlet passage and is connected to a flexible conduit 38 having a suitable discharge nozzle 40 secured thereto for discharging lubricant at any desired point. 15 Spring pressed ball check valves 42 are provided in the inlet and outlet passages to control the flow of lubricant.

A cylindrical sleeve 44 is secured in the cylinder 32 and a piston 46 slidably fits therein. The sleeve may be held in place by a cup member 48 screw threaded or otherwise suitably secured to the block 30 and this cup member may also hold a packing for the piston. The piston has secured at its outer end a disc 50 and a suitable coil spring 25 52 acts between this disc and the block to urge the piston out of the cylinder.

A support in the form of an annular ring 54 is rigidly secured to the block 30 by means of posts or legs 56. As shown, four posts are provided but 30 it will be obvious that any desired number might be used.

In order to operate the piston, operating mechanism is provided constituted by a hub 58 and an annular ring 60 connected by a plurality of rigid 35 spokes 62. The hub rests on the ring 54 and is preferably depressed in its central portion to provide an annular groove in which the ring rests, as clearly shown in Fig. 2. A suitable pin 64 is preferably secured to the hub having a rounded head 40 on which the end of piston 46 rests. The ring 60 is of sufficient diameter to encircle the lower part of the reservoir and spokes 62 are curved to raise this ring above the plane of the hub.

The ring 60 may be operated by hand or in any other desired manner but in the form shown is particularly adapted to be depressed by the foot of an operator. Downward pressure on the ring 60 at any point rocks the operating member about that point on the support 54 closest to the point at which pressure is applied as indicated in dotted lines in Fig. 2. This raises the piston 46 in the cylinder forcing lubricant past the outlet check valve and out the outlet and nozzle 40. 55 Upon release of the pressure on ring 60, the

spring 52 forces the piston downwardly, creating a void in the cylinder which is filled by grease from the reservoir flowing into the cylinder through nipple 28. The piston also presses on pin 64 pressing the operating member against the support and returning it to the full line position of Fig. 2. The operation can be repeated at will by again depressing ring 60, each operation forcing a charge of lubricant out through 10 the nozzle.

Thus by the present invention there is provided a novel pump which is simple in construction and operation, has few moving parts which are apt to get out of order, and which can be 15 operated from any desired point.

While only one embodiment of the invention has been shown and described, it will be apparent to those skilled in the art that various changes might be made therein or that the same 20 might be embodied in other forms without departing from the scope of the invention.

For example, instead of a complete annular 25 operating ring, a segment or a plurality of segments might be employed either lying in a horizontal plane as shown, or lying in a vertical plane for hand operation. Also, instead of resting loosely on its operating member, the pump plunger might be connected thereto as by a link. Various other changes might also be made and 30 it is therefore, not intended that the scope of the invention shall be limited to the form shown nor otherwise than by the terms of the appended claims.

What is claimed is:

35 1. A pump comprising a reservoir, a cylinder rigidly secured at one end thereof in communication therewith, a piston in the cylinder, and operating means for the piston including an annular portion encircling the reservoir and oper- 40 able from any point to move the piston.

2. A lubricant dispenser comprising a vertical reservoir, a vertical cylinder rigidly secured at the lower end thereof in communication therewith, a piston slidable in the cylinder, and an annular operating member for the piston lying in a horizontal plane and operable from any point to move the piston. 5

3. A lubricant dispenser comprising a vertical reservoir, a vertical cylinder rigidly secured at the lower end thereof in communication therewith, a piston slidable in the cylinder, an annular ring secured to the cylinder and an operating member having a part engaging the annular ring, a part engaging the piston and an annular portion encircling said reservoir. 10 15

4. A pump comprising a cylinder, a piston slid- 20 able therein, an operating member having an annular groove in a plane perpendicular to the axis of the cylinder, and an annular support se- cured to the cylinder and lying in said groove whereby the operating member can pivot about any point on said annular support. 25

5. A pump comprising a cylinder, a piston slid- 30 able therein, an annular support fixed relative to the cylinder, an operating member having an annular groove receiving and resting on said support, and resilient means urging the piston against the operating member and the operating member against the support, said operating mem- ber being rockable about any point in the circumference of the support as a pivot to move the piston. 35

6. In a pump, an operating member comprising a hub portion, an annular ring spaced from the hub portion, and spokes connecting said hub portion and ring, said hub portion having an external annular groove for engagement with a support. 40
